No. 629,848.

Patented Aug. 1, 1899.

W. A. DOWNES.

GAGE GLASS.

(Application filed Nov. 29, 1897.)

(No Model.)

UNITED STATES PATENT OFFICE.

WILLIAM A. DOWNES, OF DETROIT, MICHIGAN, ASSIGNOR TO THE PEN-BERTHY INJECTOR COMPANY, OF SAME PLACE.

GAGE-GLASS.

SPECIFICATION forming part of Letters Patent No. 629,848, dated August 1, 1899.

Application filed November 29, 1897. Serial No. 660,058. (No model.)

To all whom it may concern:

Be it known that I, WILLIAM A. DOWNES, a citizen of the United States, residing at Detroit, in the county of Wayne and State of Michigan, have invented certain new and useful Improvements in Gage-Glasses, of which the following is a specification, reference being had therein to the accompanying drawings.

10 My invention relates to that class of water-gage glasses in which the connecting-fittings are provided with a check-valve adapted to automatically close upon the breaking of the glass.

15 Heretofore water-gages have been made provided with various forms of check-valves, for the purpose above described. These have, however, all been subject to a serious defect, which has rendered their employment objectionable if not positively dangerous—viz., the liability of the valve being closed by the sudden fluctuation of the water in the passage caused by the operation of the blow-off valve, thus causing the glass to give a false indication 25 of the boiler water-level.

20 My invention has for its object the overcoming of this objection; and it consists in the peculiar construction and location of the check-valve employed, which in its open position is shielded from the direct impact of the current passing from the boiler to the glass; further, in the peculiar arrangement of said valve in connection with a hand-operated shut-off or blow-off valve, and, further, in the peculiar construction, arrangement, and combination of parts, as more fully 35 hereinafter described and claimed.

30 In the drawings, Figure 1 is a horizontal section through one of the connecting-fittings for my gage-glass, showing the ball check-valve therein. Fig. 2 is a vertical section on line $\alpha\alpha$, Fig. 1; and Fig. 3 is a vertical central section through a modified form of fitting.

45 A is the fitting forming one of the connections between the boiler and the glass tube of the gage. In Fig. 1 I have shown this fitting as constructed for a double gage-glass and consisting of the horizontal nipple a and 50 the oppositely-extending lateral branches b , b' , connected with the nipples B , B' , which are

provided with suitable means for securing one end of the gage-glass thereto. Within each of these branches b , b' is arranged an automatic check-valve, which in its open position is shielded from the direct impact of the current passing from the boiler toward the glass. For these valves I preferably employ the balls D , adapted to seat against the seats C and when released therefrom to roll down 60 into pockets E , formed by the L-shaped wings or shields c , the bottom of the fitting being suitably inclined to direct the balls into these pockets.

65 L is a passage leading to the blow-off cock from a point in rear of the shields c .

In the construction shown in Fig. 3 the pocket E is formed by the shield or diaphragm F , which separates it from the direct passage G , leading from the valve to the glass.

70 H is a double-seated valve having the screw-threaded shank I passing out through the nipple J of the casing and adapted in one position to engage with the seat K and close the blow-off passage L and in its opposite position to open this blow-off passage and engage with the seat M , thus shutting off connection with the boiler. This valve passes through the pocket E and forms a movable support 75 for the ball when in the pocket.

80 In the use of the gage the ball or balls D will normally lie in the pockets E , in which they are shielded from the current in the direct passage through the fitting, and thus will not be disturbed either by the ordinary fluctuations of the current in said passage or by the rush of water and steam incident to the manipulation of the blow-off cock, the current in the latter case being so directed as to tend to hold the balls in the pockets. Should, however, the glass be broken, the great rush of water through the passage toward the glass will create a suction or eddy current which will draw the ball out of the pocket and force it to its seat.

85 The object of the construction shown in Fig. 3 is to prevent danger of the ball sticking, due to the collection of sediment around it in the pocket. This is accomplished by resting the ball upon the movable part of the valve H , which as it is operated from time to time will move the ball and turn it in the 90 95 100

pocket. The pocket E is also in direct line with the blow-off passage L, and thus when the valve is moved to open the latter any sediment which may have collected in the pocket will be blown out.

5. What I claim as my invention is—

1. The combination with the connecting-fitting for a gage-glass, having a passage therethrough from the boiler to the glass, of a receptacle at one side of the passage, a shield between the receptacle and passage, and a valve in said receptacle behind said shield normally out of the current through said passage, and adapted on the breaking of the 15 glass to be drawn from behind the shield and moved to close the passage.

2. The combination with the connecting-fitting for a gage-glass having a passage therethrough from the boiler to the glass, of a 20 shield or diaphragm extending into and longitudinally of said passage and forming a pocket, and a valve in said pocket normally out of the current through said passage, substantially as described.

25. 3. The combination with the connecting-fitting for a gage-glass having a passage therethrough from the boiler to the glass, of a diaphragm or shield extending into and longitudinally of said passage and forming a

pocket opening toward the gage-glass, a blow-off valve back of the closed side of said pocket, and a valve in said pocket normally out of the current through said passage, substantially as described.

4. In a gage-glass the combination with the 30 connecting-fitting for the glass having a hand-operated valve therein, of a ball check-valve in said fitting normally resting on a movable portion of said hand-valve, and a shield independent of said hand-operated valve adapted 40 to protect said ball-valve in its normal position from the direct impact of the current passing through said fitting toward the glass.

5. In a gage-glass the combination with the connecting-fitting for the glass having a hand-operated blow-off valve therein, of a shield 45 independent of said valve forming a pocket out of line with the direct passage through said fitting toward the glass, and in line with the blow-off passage, and a ball check-valve 50 normally resting in said pocket upon a movable portion of said hand-valve.

In testimony whereof I affix my signature in presence of two witnesses.

WILLIAM A. DOWNES.
